UNITED STATES PATENT OFFICE.

GIOVANNI SIECKENBERGER, OF NEW YORK, N. Y.

DESIGN FOR A LAMP-FIXTURE.

SPECIFICATION forming part of Design No. 15,061, dated June 10, 1884.

Application filed March 24, 1883. Term of patent 7 years.

To all whom it may concern:

Be it known that I, GIOVANNI SIECKENBERGER, of New York, in the county of New York and State of New York, have invented 5 a new and original Design for Lamp-Fixtures, of which the following is a specification.

This design is especially intended for a hanging lamp.

The accompanying illustration is a perspective view of a lamp embodying the design.

The pendent frame in which the lamp is supported consists of a scroll, *a*, arranged between two plain bands, *b*, terminating in wheel-like portions *c*. Beyond these devices are dragon-like figures *d*. From the necks of the dragon-like figures bands *e* extend to arms *f*. At the top of the shade *i* is a crown, having along the lower edge a number of angular portions, *j*, and along the upper edge a number of arc-shaped portions, *k*, and intervening angular portions *l*. The arc-shaped portions *k* are em-

bellished with fleur-de-lis *m*. Claw-shaped loops *g* receive suspending-chains *h*. The hanger of the lamp has along the outer edge a number of arc-shaped portions, *n*, and intervening angular portions *o*. The parts *a b c* 25 form a bow-shaped portion extending between the dragon-like figures *d*.

What I claim as my design, and desire to secure by Letters Patent, is— 30

1. The design for a lamp-supporting frame, comprising dragon-like figures, arms extending above the same, and a bow-shaped portion extending between the same, substantially as shown and described. 35

2. The design for a lamp-shade crown, substantially as shown and described.

GIOVANNI SIECKENBERGER.
